UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING-MACHINE CASE.

Application filed November 12, 1920. Serial No. 423,613.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting-Machine Cases, of which the following is a specification.

- This invention relates to an improved 10 cover-lock or fastening means, and is in the form of releasably interlocking parts, and the object of the invention is to provide a construction which is easier to operate than the constructions already in use.
- 15 The invention not only has the advantage that, by inserting tongues provides on the cover into sockets formed on the rear edge of the base-board, the parts may be interlocked, and there held by securing the front 20 of the cover to the front of the baseboard, but it has the further object that the tongues may be made rounded, preferably cylindrical, and fitted closely in the sockets, so as to prevent relative up and down movement or 25 shaking of the baseboard after the cover is in place therearound, thereby making the whole structure firm, tight and strong, and not liable to cause trouble, and not requiring undue attention either when attaching the 30 cover to the baseboard or while the machine is being transported. The tongues are in a protected position on the inside of the cover, so that they are not liable to damage when the cover is standing on the floor or being 35 taken from place to place. The tongues readily enter the sockets at any angle to which the cover is tilted in drawing it onto the baseboard, which is enclosed by the cover.
- 40 Other features and advantages will hereinafter appear.

In the accompanying drawings,

Figure 1 represents a sectional view of a baseboard and cover with my improved fastening means shown connecting the two.

Figure 2 is a horizontal sectional view.

Figure 3 is a sectional view with the cover and base-plate separated.

Figure 4 is a perspective view of the fastener parts separated.

Referring to the drawings, 1 indicates a depression or cavity formed in the rear edge of and near each end of a baseplate 2. Preferably each depression is protected by a 55 metal piece formed as indicated in Figure

4 and fastened to the baseplate by wood screws 3. Co-operating with the depression, which, in effect, constitutes one portion of a hinge, is a second portion of the hinge formed by a metal loop 4 rolled up as indicated in Figure 4 and secured to the cover 5. Within the enclosure formed by the baseplate 2 and cover 5, a portable typewriter 6 may be suitably supported by brackets 7 and 8, although, of course, it is 60 obvious that the case formed by the baseplate and cover may be used for carrying other things. Suitable means, such as a catch or latch 9, which may be of any well-known or suitable construction, is provided 65 whereby the baseplate and cover are held together at a different point from what may be considered the rear portion.

With my improved form of hinge or fastening means, it is much easier to put the 70 cover on the baseboard than in prior constructions, the two being interlocked as soon as the cover is fastened to the baseplate at the point 9. It will be readily seen that as the cover is being drawn on, the loops 4 75 will slide into the corresponding depressions formed in the baseboard, and, when the fastening 9 is in position, the cover and baseboard will be securely locked together. While I have shown the depressions in the 80 baseboard and the loops fastened to the cover, it is, of course, obvious that these positions may be reversed.

It will be seen that, by having sockets in the rear edge of the baseboard, the tongues 85 may be made to protrude forwardly from the rear wall of the cover, but above the bottom edge thereof, so that said tongues are not apt to get bent or struck or exposed to injury. Since the baseboard is surrounded 90 by the cover, the operation of removing the cover consists first in unlocking the cover at the front, and then lifting the front end of the cover, whereby the cover is tilted, and hence the tongues at the rear of the cover 95 tilt in the sockets. In order to avoid extremely loose fitting of the tongues in the sockets, which would otherwise be necessary in order to permit the cover so to tilt, the tongues are made of cylindrical form, so 100 that they fit tightly at all times in the sockets, and rattling and looseness between the cover and the baseboard are avoided; while, owing to their cylindrical form, the tongues 105 permit the cover to tilt up. Moreover, the 110

tongues, because of their rounded form, are adapted to enter the sockets readily at any angle to which the cover presents them to the sockets, when the cover is being dropped 5 into place on the baseboard.

Variations may be resorted to within the scope of the invention, and portions of the improvements may be used without others.

Having thus described my invention, I 10 claim:

1. In a device of the character described, in combination, a typewriter baseboard, and a typewriter cover detachably joined thereto by a catch provided upon the rear of the 15 cover and extending into a socket provided in the rear edge of the baseboard.

2. In a device of the character described, in combination, a typewriter baseboard and a cover therefor, one of said parts having 20 a plurality of sockets therein, and the other part having tongues for engagement with the sockets, and means for fastening the cover and baseboard together at another point, said tongues and sockets interlocking 25 to lock the cover detachably to the baseboard.

3. In a device of the character described, in combination, a typewriter baseboard and detachable cover, one of said parts having a 30 plurality of metallic loops to form locks or catches, and the other a plurality of sockets into which the loops seat.

4. In a device of the character described, in combination, a typewriter baseboard and 35 detachable cover, one of said parts having a plurality of metallic loops to form locks or catches, and the other a plurality of sockets into which the loops seat, and means for fastening the cover to the baseboard at an 40 other point.

5. In an enclosing device or casing, in combination, a typewriter baseboard and a cover fitting over said board, and means for 45 removably securing the cover-part on the baseboard-part, comprising a recess forming a socket in the rear edge of the baseboard and a projection on the cover to engage in and be released from the socket by an angular lifting movement of the front of the 50 cover.

6. In an enclosing device or casing, in combination, a baseboard, a cover to enclose the baseboard, a metallic socket-member countersunk into one of said parts, and a metallic catch-member carried by the other 55 of said parts and having a rounded projection to fit into said socket, for detachably fastening said parts tightly together.

7. The combination of a typewriter baseboard and a detachable typewriter cover to 60 fit over the baseboard, said baseboard having sockets, in its rear edge, and said cover having corresponding tongues or projections rounded to fit closely in said sockets when the cover is in place on the board, and to 65 enter freely said sockets as they are presented thereto at any angle in drawing the cover upon the baseboard.

8. The combination of a typewriter baseboard and a detachable typewriter cover to 70 fit over the baseboard, said baseboard having sockets, in its rear edge, and said cover having corresponding tongues or projections rounded to fit closely in said sockets when the cover is in place on the board, and to 75 enter freely said sockets as they are presented thereto at any angle in drawing the cover upon the baseboard; and means at the front of the cover and baseboard to secure them together. 80

9. The combination of a typewriter baseboard and a detachable typewriter cover to fit over the baseboard, said baseboard having sockets, in its rear edge, and said cover having corresponding tongues or projections 85 rounded to fit closely in said sockets when the cover is in place on the board, and to enter freely said sockets as they are presented thereto at any angle in drawing the cover upon the baseboard; and means at the 90 front of the cover and baseboard to secure them together, each socket having a lining of sheet-metal fitted thereto, and each tongue in the form of a metal plate having a rolled-up portion or loop to fit closely in 95 said lining.

ALFRED G. F. KUROWSKI.
